DESIGN FOR A BOTTLE

Raymond Loewy, New York, N. Y., assignor to Eversharp, Inc., Chicago, Ill., a corporation of Delaware

Application September 16, 1942, Serial No. 108,241

Term of patent 14 years

To all whom it may concern:

Be it known that I, Raymond Loewy, a citizen of the United States, residing at New York, in the county of New York and State of New York, have invented a new, original, and ornamental Design for a Bottle, of which the following is a specification; reference being had to the accompanying drawing, forming a part hereof.

In the drawing:

Fig. 1 is a perspective view of a bottle embodying my new design;

Fig. 2 is an elevational view of same; and

Fig. 3 is another elevational view of same at approximately 90° from that shown in Fig. 2.

I claim:

The ornamental design for a bottle, substantially as shown.
